UNITED STATES PATENT OFFICE

157,991

RAIN TROUGH FOR AN AUTOMOTIVE
VEHICLE SWINGING WINDOW

Robert J. Mauck, Detroit, Mich.

Application April 10, 1943, Serial No. 145,636

Term of patent 14 years

(Cl. D14—6)

To all whom it may concern:

Be it known that I, Robert J. Mauck, a citizen of the United States of America, residing at Detroit, in the county of Wayne and State of Michigan, have invented a new, original, and ornamental Design for a Rain Trough for an Automotive Vehicle Swinging Window, of which the following is a specification, reference being made to the accompanying drawing, forming part thereof.

Fig. 1 is a side elevation, showing my rain trough for an automotive vehicle swinging window;

Fig. 2 is a side elevation taken from the opposite side of that shown in Fig. 1;

Fig. 3 is an end elevation looking forwardly down the trough toward the upturned forward end of the same.

I claim:

The ornamental design for a rain trough for an automotive vehicle swinging window, substantially as shown.

ROBERT J. MAUCK.
